UNITED STATES PATENT OFFICE.

KARL ENGEL, OF ARLINGTON HEIGHTS, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PROCESS OF MAKING SHOES.

1,360,277.

Specification of Letters Patent. Patented Nov. 30, 1920.

Application filed March 22, 1916. Serial No. 85,807. Renewed April 14, 1920. Serial No. 373,931.

To all whom it may concern:

Be it known that I, KARL ENGEL, a citizen of the United States, residing at Arlington Heights, in the county of Middlesex and State of Massachusetts, have invented certain new and useful Improvements in Processes of Making Shoes; and I do hereby declare the following to be a full, clear, and exact description of the invention, such as will enable others skilled in the art to which it appertains to make and use the same.

This invention relates to a process of making shoes and more particularly to a process of making welted and turned shoes.

In the present commercial process of making welted and turned shoes after the upper and insole or single sole have been prepared for assembling and have been assembled upon a last the upper is lasted or stretched tightly about the last so as to cause it to conform substantially to the shape of the last at all points by gripping the lower marginal portion of the upper and drawing it with considerable force over the marginal portion of the sole and the upper is then secured in position at its margin by temporary fasteners. The lasting operation is performed by hand or by a machine especially constructed for this purpose. In this process of making shoes the upper is cut so as to provide a considerable surplus of material at its lower margin which is essential in order to enable the lasting grippers to secure a firm grip on the upper during the lasting operation. This surplus or excess in the material of the upper which projects beyond the inseam after the inseam is sewn is trimmed off in the inseam trimming operation. Upper leather is expensive and the surplus material in the upper which is trimmed off and wasted adds considerable to the expense of the shoe.

One object of the present invention is to provide a process of making welted and turned shoes by which such shoes in every respect as good as those made in accordance with the present commercial process may be manufactured with a considerable saving in the cost of production.

Another object of the invention is to provide a process of making welted and turned shoes by which the waste in the upper leather incident to the present com-

mercial process may to a large extent be eliminated.

55

With these and other objects in view the invention consists in the process hereinafter described and defined in the claims.

In the accompanying drawings are illustrated the parts of a welted shoe at different stages in the manufacture of the shoe in accordance with applicant's process, but it is to be understood that the invention broadly considered is applicable to the manufacture of other types of shoes and that except as defined in the claims the invention is not limited in its application to making any particular type of shoe.

In the drawings Figures 1 and 2 are plan views showing the insole and upper before they are assembled and before the upper is molded; Fig. 3 is a perspective view, partly in section, of the insole and upper assembled ready to be sewn showing the manner in which the upper is molded prior to placing the insole in position; Fig. 4 is a detail plan view of the toe portions of the upper and insole when assembled as in Fig. 3; Fig. 5 is a perspective view, partly in section, illustrating the shoe after the inseam is sewn; Fig. 6 is a view illustrating the manner in which the welt and the feather of the insole are beaten out before the outsole is laid; Fig. 7 is a central longitudinal sectional view illustrating the shoe after the outsole has been laid and sewn to the welt; Fig. 8 is a perspective view illustrating the manner in which the shoe is stretched prior to the insertion of a complete last; and Fig. 9 is a perspective view illustrating the finished shoe with the complete last inserted.

In preparing the upper of the shoe for attaching it to the insole in accordance with applicant's process, the upper, indicated at 1, is cut substantially to the size which it is to have in the finished shoe, neglecting the stretching or lasting to which the upper is subjected after the insole, indicated at 2, and the upper are attached together at their marginal portions by permanent fastenings. Before the upper and insole are assembled the toe portion of the upper and preferably the heel portion also are molded into shape as illustrated in Fig. 3. In the upper molding operation the toe portion of the upper above the line along which the stitches or

other fastenings are to be inserted to attach the upper to the insole is molded and stretched so as to give it substantially the shape of the last and the marginal portion 5 of the upper at the toe is formed in plaits or folds substantially as in the lasting operation of the ordinary process of manufacture of welted and turned shoes. As will be noted from an inspection of Fig. 3, the 10 upper is molded inwardly at 3 so that it will lie properly over the margin of the insole and is turned outwardly at 4, thereby forming a convexed shoulder 5 for engagement with the shoulder at the outer margin of 15 the between-substance of the sole and a crease 6 in which the margin of the welt, indicated at 7, Fig. 5, is laid in attaching the welt and upper to the insole. This molding of the upper amounts in effect to a preliminary lasting operation in which the toe of 20 the unlasted upper is molded substantially into the shape of the toe of the upper of a lasted shoe. The heel of the upper is molded as shown in Fig. 3 with the lower marginal 25 portion of the upper shaped at an angle to the upper portion thereof so that it will lie over the heel of the insole. The toe of the upper is molded after the toe box 8, if such is used, has been inserted between the lining 30 9 and the upper leather, and the upper, toe box and lining are all molded together into the shape shown in the drawings. In order to cause the upper to hold its shape after having been molded and especially to retain 35 the folds or plaits formed in the marginal portion thereof, size or cement is inserted preferably between the toe box and the upper leather and the forms by which the upper is molded are heated so that the upper 40 after being removed from the forms sets in the position in which it is molded. This molding of the upper is an important feature of applicant's process since it shapes the marginal portion of the upper so that 45 it will fit properly about the toe of the insole when the upper and insole are assembled and so that it will conform accurately to the last when the last is inserted.

At the same time that the toe and heel 50 portions of the upper are molded or as an intermediate step between the upper molding operation and the sewing of the upper to the insole, the parts of the upper which are not shaped by the toe and heel molding operations may be stretched to take more or less of the stretch out of the upper, to bring the upper more nearly to its proper size and to shape to a certain degree these parts of the upper.

60 The insole employed may be constructed in accordance with any one of several well-known types. The insole shown in the drawing is provided with a channel lip 10 which is formed by an oblique cut extending 65 about the marginal portion of the insole and

has the outer portion of its margin cut away in a plane parallel with the plane of the insole forming a shoulder 11, and a thin flexible portion 12 at the outer edge of the insole which is ordinarily termed the feather.

70 In assembling the upper and insole the insole is placed inside the upper with the heel of the insole beneath the inwardly molded portion of the upper at the heel and the heel of the upper is preferably attached to 75 the heel of the insole by a tack 13 or other fastener. When the insole and upper are thus assembled they are ready to be attached together by stitches passing through the between substance of the insole and the margin of the upper. The stitching together 80 of the upper and insole is performed with the upper in an unlasted condition, or without the placing of a last on other supporting form within the upper to support either the 85 upper or the insole. In the operation of sewing the upper to the insole the lower margin of the upper is placed over the margin of the insole and the edge of the upper is preferably gaged so that it projects a 90 substantially uniform distance beyond the base of the shoulder of the between substance or beyond the stitch line, such that practically no excess or surplus material of 95 the upper is left projecting beyond the inseam after the seam is sewn. The sewing of the upper to the insole in this manner together with the welt may be performed upon a machine constructed as illustrated and described in the application of Frederic 100 Bertrand, Serial No. 861,215, filed September 11, 1914, or upon any other suitably constructed machine, or it may be performed by hand. The upper is preferably not attached to the insole completely around 105 the insole by the inseam, but is left unattached along the heel of the insole, or at least along a portion of the heel. When the inseam has been sewn the unattached portion 110 of the upper is drawn taut over the heel of the insole and is attached thereto preferably by a series of tacks. This manner of attaching the upper to the insole enables the upper, if its lower margin happens to be too large to fit accurately the 115 margin of the insole, to be attached to the insole without producing folds or puckers in the margin of the upper which will be visible in the finished shoe.

120 If for any reason, such as the inaccurate guiding or gaging of the upper during the sewing operation, there is any surplus upper material projecting beyond the inseam after the upper, welt and insole are sewn together, this surplus is trimmed off preferably directly after the inseam is sewn. This trimming operation may be performed upon a disk knife skiving machine or other suitable trimming machine, or the upper may 125 be trimmed off by means of a hand knife. 130

In actual practice it has been found that when the parts of the shoe are prepared, assembled and sewn together in accordance with the present process of manufacture, it is unnecessary to trim off the upper except in a very small number of shoes.

When the upper, welt and insole are sewn together without a last or other supporting form within the upper, the marginal portion or feather of the insole projecting beyond the between substance is ordinarily bent to a considerable degree out of the plane of the body of the insole during the sewing operation. In a welted shoe the feather gives the proper bulge or overhang to the upper just above the line of the inseam and determines to a great degree the shape of the shoe and when the feather is bent unduly away from the plane of the body of the insole, it allows the upper to draw away from the welt, thus giving the shoe an irregular and unfinished appearance. In applicant's process of manufacture of welted shoes, after the inseam is sewn the welt is beaten out flat in substantially the same manner as in the ordinary process of manufacture of such shoes, and the feather of the insole is also bent back into the place of the insole and set in position by subjecting the margin of the insole to a beating operation similar to that performed on the welt.

In the operation of beating out the welt and the feather as preferably performed a support such as that indicated at 14, Fig. 6, is inserted in the shoe in position to engage the inner face of the margin of the insole and support the feather in the plane of the body of the insole and the welt of the shoe is placed upon a suitable support such as indicated at 15, the welt support being shaped to enter the crease between the upper and the welt and located with its upper surface substantially parallel with the upper surface of the feather support 14. The feather and the welt while supported substantially in the plane of the body of the insole respectively by the feather support and the welt support are beaten out in one operation by the blows delivered by a hammer such as that indicated at 16. The hammer is rapidly reciprocated in a direction substantially perpendicular to the upper surfaces of the feather and welt supports. The hammer is arranged to extend over the welt across the inseam and over the marginal portion of the insole so that it acts to beat out and set the welt and the feather of the insole in substantially the plane of the body of the insole and also to beat the projecting edges of the welt and upper down into substantially the plane of the outer face of the insole.

The beating out of the welt and feather reduces the shoe to the proper condition for the laying of the outsole. In order to sup-

port the insole during the sole-laying operation the bottom of a divided last such as that shown at 17, Fig. 7, is inserted in the shoe. The outsole may be laid in applicant's process in substantially the same manner as 70 in the commercial process of making welted shoes. In preparing the outsole it is preferably cut substantially to its final outline or substantially to the shape and size it is to have in the finished shoe, before it is applied 75 to the shoe. In the ordinary process of making welted shoes it is practically impossible to cut the outsole to its final outline before it is laid. It is obviously essential to the correct appearance of the shoe that the outsole after it is applied to the shoe project the proper distance beyond the inseam at all points. In the operation of sewing together the welt, upper and insole as performed in the regular commercial process of manufacture of welted shoes, the operator exerts a comparatively heavy strain or pull upon the shoe against the channel guide. Considerable strain also is exerted upon the between substance by the stitches themselves 80 as they are drawn taut to draw the upper and between substance tightly together. The stock of the insole is then in a tempered condition and is easily stretched out of shape, and the result is that during the sewing operation the between substance of the insole is pulled out of its natural or proper position and that the marginal portion of the insole is stretched out of its proper shape at 85 certain points. This stretching of the material of the insole and displacement of the position of the inseam is never the same in any two shoes of the same size and style, so that it is obviously impossible to cut the outsole so that when it is applied to the shoe it 90 will project the proper distance beyond the inseam at all points in its marginal portion. In applicant's process of making welted shoes the welt, upper and between substance of the insole are drawn together by the 100 stitches against practically no resistance whatever, and there is no pull or strain exerted upon the parts of the shoe against the channel guide and consequently substantially no outward stretching force exerted by the 105 channel guide upon the between substance as in the commercial process. The marginal portion of the insole, therefore, is not stretched out of shape or the between substance displaced at any point during the 110 sewing operation, so that the inseam occupies its natural and proper position after the welt and upper are attached to the insole. For this reason, the outsole may be cut to its final outline before it is applied to the shoe, thereby 115 enabling the rough-rounding operation to be eliminated.

Outsoles cut in block form may be employed, and in that event after the outsole is laid upon the lasted shoe bottom the out- 120

sole is rough-rounded, preferably by presenting the shoe to a suitable rough-rounding machine. In this operation the marginal portion of the sole is trimmed off at the 5 proper distance from the inseam.

The shoe is then ready for the stitching of the outsole of the welt. The outsole stitching operation does not differ from the outsole stitching operation in the regular 10 process of making welt shoes, and may be performed upon any suitable stitching machine for stitching outsoles.

After the upper has been attached at its lower margin to the insole and preferably 15 after the outsole is stitched to the welt, the upper is subjected to a stretching operation to take the stretch out of the upper and to give the upper its proper shape and size, and a last is then inserted in the shoe to hold 20 the upper in shape. The stretching operation may be performed at any convenient stage in the manufacture of the shoe after the upper is attached to the insole but is preferably deferred until after the outsole is attached, 25 since the insole is then much less liable to be stretched and the inseam displaced or distorted than before the outsole is attached.

In the stretching operation as preferably 30 performed suitably shaped blocks or forms are placed within the toe and heel of the shoe and the upper is stretched by moving these blocks relatively in opposite directions from the central portion of the shoe bottom outwardly. In Fig. 8 the shoe is shown with a 35 heel form 18 shaped to fit the inside of the shoe at the heel located within the heel of the shoe and with two forms 19 and 20 pivoted together at 21 and having substantially the shape of the interior of the forepart of the shoe located within the forepart of the shoe. With stretching forms such as these applied to the inside of the shoe the upper may be stretched by relatively moving the heel form 18 and the two forepart forms 40 away from each other in a direction lengthwise of the shoe and at the same time swinging the forepart forms 19 and 20 outwardly on the pivot 21. In this way the upper is 45 stretched longitudinally of the shoe for substantially the whole length of the shoe and the forward portion of the upper is stretched laterally to a progressively increasing extent from the toe toward the ball. This manner of stretching the upper has certain marked 50 advantages over the ordinary method of stretching or lasting. In the lasting operation as usually performed in the commercial process of making shoes, the upper is often 55 over-stretched and sometimes torn at the 60 separated points at which the lasting pincers or grippers are applied, while at intermediate points the upper is not sufficiently and properly stretched. Furthermore, in this 65 operation the upper is drawn by the grippers over the bottom of the last with the result

that the upper is stretched chiefly between the last bottom and the grippers, and comparatively little stretching strain is given to the upper above the last bottom. In the upper-stretching operation as performed in 70 accordance with the present process of manufacture, substantially the whole of the upper is subjected to a stretching force from within while its lower margin is secured to the shoe bottom by the expansion or relative 75 movement of the stretching forms with the result that the upper is subjected to the required stretching strain at substantially all points to give it the proper shape and size.

After the upper has been properly 80 stretched a complete last is inserted in the shoe. In order to facilitate the insertion of the last which should fit tightly in the shoe, the last is divided as shown along the curved line y, Fig. 7, forming a bottom portion 17 85 shown in section in Fig. 7, and an upper forward portion 22. The bottom portion 17 is arranged to fit over the whole interior of the shoe bottom and to fill the heel of the shoe. Before the last is inserted in the shoe 90 the parts of the last are separated and the bottom portion is first located within the shoe as shown in Fig. 7. The insole is preferably cut to the exact size of the bottom of the last so that when the bottom portion is 95 placed within the shoe the marginal portion of the upper at its junction with the edge of the insole hugs tightly to the bottom of the last. The manner in which the last is divided gives the upper forward portion 22 100 of the last which is adapted to fit the upper portion of the forepart of the shoe, a tapered cross-section, increasing from the forward end thereof rearwardly. This shape of the portion 22 of the last enables it to be easily 105 driven into place in the shoe after the bottom portion 17 has been inserted.

When the complete last has been inserted in the shoe, the shoe may be finished in substantially the same manner as in the ordinary commercial process of manufacture of 110 welted shoes.

In cutting the upper of the shoe substantially to the size which it is to have in the finished shoe, and sewing it to the sole in 115 such a manner that no surplus material of the upper is left projecting beyond the inseam, the upper stock which is trimmed off in the upper trimming and inseam trimming operations of the commercial process is 120 saved. It has been found in actual practice that the saving in upper stock brought about by applicant's process may be as high as 33% of the amount required in the commercial process of manufacture of welted 125 and turn shoes. In addition to the saving in the upper stock which is brought about by applicant's process of manufacture of shoes, a considerable saving in lasts also results from this process. In the ordinary 130

commercial process of manufacture of welted and turn shoes, the upper and sole remain upon the last from the time when they are first assembled until the shoe is finished, 5 while in applicant's process the last is not inserted until after the sewing of the inseam. Since the shoe remains on the last a much shorter time in applicant's process than in the commercial process, the number 10 of lasts which are required in a shoe factory in which shoes are made by applicant's process is much less than the number required in a factory in which the commercial process is followed. Applicant's process of manufacture of welted and turned shoes also reduces considerably the amount of labor required in the making of the shoe which results in a further reduction in the cost of manufacture.

In the present process applicant eliminates 20 the pulling over and the lasting operations, the tack driving operation, the tack pulling and resetting operation, and ordinarily the inseam trimming and rough-rounding operations. The only operations included in this 25 process which do not form a part of the regular commercial process are the upper molding and stretching operation, the upper stretching operation performed after the upper and insole are attached and the insertion 30 of the last in the shoe, which obviously require much less labor and time than the operations which are eliminated. Welted and turned shoes made in accordance with this process have substantially the same construction and are in all respects as good as 35 the shoes made by the commercial process, and the shoes may be manufactured at a greatly reduced cost due to the reduction in the amount of stock, the number of lasts 40 and the amount of labor required.

It is to be understood that the term "upper" is employed in its generic sense in the claims and may include the usual parts such as upper leather, lining and toe and 45 heel stiffeners.

It is also to be understood that the term "unlasted" as employed in the claims signifies that the parts are not applied to a last and does not indicate that the parts have 50 received no preliminary stretching or shaping.

Having explained the nature and object of the invention and having specifically described the preferred embodiment thereof, 55 what is claimed is:

1. The process of making shoes which consists in preparing an insole having a lip and a marginal portion or feather projecting beyond the lip, placing the marginal 60 portion of an upper over the outer face of the marginal portion of an insole and attaching the upper and a welt to the between substance of the insole in an unlasted condition, beating out the feather of the insole 65 and the welt to cause them to lie substan-

tially in the plane of the body of the insole and attaching an outsole to the welt.

2. The process of making shoes which consists in attaching an upper and a welt to an insole in an unlasted condition, attaching an outsole to the welt and stretching the upper after the outsole is applied. 70

3. The process of making shoes which consists in attaching an upper and a welt to an insole in an unlasted condition, cutting an 75 outsole substantially to its final outlines, attaching the outsole to the welt and stretching the upper after the outsole is applied.

4. The process of making shoes which consists in attaching an upper and a welt to 80 an insole in an unlasted condition, inserting a last bottom in the attached upper and insole, cutting an outsole substantially to its final outline, laying the outsole, attaching the outsole to the welt and stretching the 85 upper after the outsole is applied.

5. The process of making shoes which consists in molding an upper to give it substantially the shape of a lasted shoe upper, attaching the upper and a welt to an insole 90 in an unlasted condition, attaching an outsole to the welt and stretching the upper after the outsole is applied.

6. The process of making shoes which consists in cutting an upper substantially to 95 the size it is to have in the finished shoe, molding the upper to give it substantially the shape of a lasted shoe upper, attaching an upper and a welt to the insole in an unlasted condition, beating out the feather of 100 the insole and the welt to cause them to lie substantially in the plane of the body of the insole, attaching an outsole to the welt and stretching the upper after the outsole is applied. 105

7. The process of making shoes which consists in stretching an upper before it is attached to a sole, then attaching the upper to a sole in an unlasted condition, again stretching the upper after the upper and sole are attached, and thereafter inserting 110 a last in the attached upper and sole.

8. The process of making shoes which consists in attaching an upper to a sole in an unlasted condition, then stretching the upper 115 before the upper and sole are applied to a last and thereafter inserting a last in the attached upper and sole.

9. The process of making shoes which consists in molding into permanent shape the 120 marginal portion of an upper at one or more points, and stretching the upper at other points, then attaching the upper to a sole in an unlasted condition, and thereafter inserting a last in the attached upper and sole. 125

10. The process of making shoes which consists in attaching a welt and an upper to an insole in an unlasted condition, cutting an outsole substantially to its final outlines, and attaching the outsole to the welt. 130

11. The process of making shoes which consists in attaching a welt and an upper to an insole in an unlasted condition, cutting an outsole substantially to its final outlines, attaching the outsole to the welt and stretching the upper.

12. The process of making shoes which consists in cutting an upper substantially to the size it is to have in the finished shoe, 10 attaching a welt and the upper to an insole in an unlasted condition, attaching an outsole to the welt, and stretching the upper.

13. The process of making shoes which consists in cutting an upper substantially to 15 the size it is to have in the finished shoe, molding the upper at one or more points, attaching the upper and a welt to an insole in an unlasted condition, beating out the welt and the feather of the insole, attaching 20 an outsole to the welt and stretching the upper.

14. The process of making shoes which consists in stretching the upper before it is attached to a sole, attaching the upper to 25 the sole in an unlasted condition, and again stretching the upper after the upper and sole are attached together and before they are applied to a last.

15. The process of making shoes which 30 consists in molding into permanent shape the marginal portion of an upper at one or more points, and stretching the upper at other points before it is attached to a sole, and attaching the upper to the sole in an 35 unlasted condition.

16. The process of making shoes which consists in attaching an upper to a sole in an unlasted condition and beating out the marginal portion of the sole while the upper 40 and sole are unlasted.

17. The process of making shoes which consists in attaching an upper to a sole in an unlasted condition, and thereafter beating out the marginal portion of the sole to cause 45 it to lie substantially in the plane of the body of the sole.

18. The process of making shoes which consists in attaching a welt and upper to an insole in an unlasted condition, and thereafter 50 beating out the welt and the feather of the insole while the shoe is unlasted.

19. The process of making shoes which 55 comprises molding an upper at one or more points to substantially its final shape and with inturned flanges to overlie the outer face of the margin of a sole, stretching the upper at other points before at least the

greater portion of its margin is attached to the sole, and thereafter inserting a line of fastenings to attach the greater part of 60 the margin of the upper permanently and securely to the sole.

20. The process of making shoes which comprises molding the toe and heel portions of an upper to substantially their final 65 shape and with inturned flanges to overlie the outer face of the margin of a sole, stretching the upper at points intermediate the toe and heel portions before at least the greater part of its margin is attached to 70 the sole, and thereafter inserting a line of fastenings to attach the greater part of the margin of the upper permanently and securely to the sole.

21. The process of making shoes which 75 comprises assembling an upper and a sole, and, with the parts in unlasted condition, attaching at least the greater part of the margin of the upper to the sole in permanent and final position with relation to the 80 sole while leaving a portion of the upper unattached to the sole at the heel, and thereafter folding the unattached portion of the upper at the heel over the outer face of the sole and securing the same in position.

22. The process of making shoes which 85 comprises cutting an upper substantially to the size it is to have in the finished shoe, assembling the upper and a sole, and, with the parts in an unlasted condition, attaching 90 at least the greater part of the margin of the upper to the sole in permanent and final position with relation to the sole while leaving a portion of the upper unattached 95 to the sole at the heel, and thereafter folding the unattached portion of the upper at the heel over the outer face of the sole and securing the same in position.

23. The process of making shoes which 100 comprises assembling an upper and a sole having a sewing rib and a marginal portion projecting beyond the rib, and, with the parts in an unlasted condition, inserting 105 a line of fastenings to attach in permanent and final position at least the greater part of the margin of the upper to the rib of the sole while leaving a portion of the upper unattached to the sole at the heel, and thereafter folding the unattached 110 portion of the upper at the heel over the outer face of the sole and fastening the same securely in position.

KARL ENGEL.

It is hereby certified that in Letters Patent No. 1,360,277, granted November 30, 1920, upon the application of Karl Engel, of Arlington Heights, Massachusetts, for an improvement in "Processes of Making Shoes," errors appear in the printed specification requiring correction as follows: Page 2, line 84, for the word "on" read *or*; page 3, line 28, for the word "place" read *plane*; and that the said Letters Patent should be read with these corrections therein that the same may conform to the record of the case in the Patent Office.

Signed and sealed this 4th day of January, A. D., 1921.

[SEAL.]

L. B. MANN,

Acting Commissioner of Patents.
